REFUSE BAG SUPPORT

Travis Otis Smith, Kansas City, Mo., assignor, by
mesne assignments, to Arbee Products Com-
pany, Kansas City, Kans., a firm composed of
David M. Lorenz and Bernhard W. Alden

Application October 26, 1945, Serial No. 624,837

2 Claims. (Cl. 248—99)

1

This invention relates to bag supports in general and particularly means for holding bags adapted to receive refuse such as kitchen garbage and the primary aim is to provide simple, inexpensive, rugged and effective equipment for mounting a refuse bag so that it may be conveniently opened and closed through a minimum number of operating parts.

This invention has for one of its salient aims the provision of a refuse bag support having a pair of jaws arranged to engage opposed stretches of the bag at the mouth thereof and simple structure for supporting the jaws for movement to and from a closed position where the mouth of the bag is maintained tightly closed to eliminate the escape of odors and to prevent the entrance of flies, gnats or other animal life that may be attracted by the contents of the bag.

Further aims of the invention will appear during the course of the following specification referring to the accompanying drawing, wherein:

Fig. 1 is a top plan view of a refuse bag holder showing the same in a condensed condition to illustrate in detail the mechanism at each end of the sack engaging jaws.

Fig. 2 is a transverse cross sectional view taken on line II—II of Fig. 1 with the jaws in a closed position.

Fig. 3 is a similar cross sectional view illustrating the jaws in an open condition or at one end of their path of travel, and

Fig. 4 is a front elevational view of the refuse bag holder with the jaws in a closed position.

The form of bag holder chosen for illustration embodies the broad features of my invention and the numeral 10 designates a bracket, substantially U-shaped in form and having a base plate 12 through the medium whereof the entire assembly may be mounted upon a supporting wall. Laterally projecting legs 14 form a part of bracket 10 and each mounts a pair of arms 16 and 18 respectively. These arms are arcuate and practically L-shaped and the means for attachment to the legs 14 are rivets 20 about which the respective arms oscillate. The free ends of the lowermost stretches of arms 16 and 18 are developed into gear segments 22 and 24 respectively and these gear segments are in mesh, as clearly shown in Figs. 2 and 3.

The arms 16 and 18 are formed of sheet material and lie in the same plane immediately adjacent to the inner face of the supporting legs 14. The opposite free ends of each of the arms 16 and 18 carry jaws 26 of like character in that each jaw comprises a strip 28 rigid to the arms

2

16 and 18 as the case may be and a swingable clamp 30 designed to grip a portion of the bag at the mouth thereof. These clamps 30 are U-shaped in transverse cross section and straddle strips 28, as clearly shown in Figs. 2 and 3.

A handle 32 mounted on one of strips 28 near its medial line affords a grip for the operator and when outward force is imparted to this handle, opposed arms 16 carrying one strip 28 will 10 be drawn toward the open side of bracket 10 and due to the intermeshing of gears 22 and 24 at each end of the assembly, the opposite arms 18 will be moved about their pivotal points of support toward the open position.

15 A spring 34 having one end anchored to arm 18 and its opposite end anchored to bracket 10, as clearly shown in Figs. 2 and 3, serves to yieldably maintain the pairs of arms 16 and 18 in either the completely closed condition, as shown in Fig. 2, or the open position, as illustrated in Fig. 3. The "past center" action of spring 34 is rendered clear in these Figs. 2 and 3 and it is also apparent from an observation of Fig. 3 that arm 18 is 20 limited in its movement toward the open position by a pin 9 on bracket 10.

When the arms are closed, clamps 30 are in juxtaposition and parallelism to form a closed mouth for the bag. The bag depends from jaws 26 and its flexibility permits unrestricted movement of the parts as above described. Simultaneous movement of arms 16 and 18 is always insured because of gears 22 and 24.

30 Simplicity of structure and positive action is the result of utilizing the assembly just described and since slight modifications as to structural details might be made it is desired to be limited only by the spirit of the invention and scope of the appended claims.

Having thus described the invention what I 40 claim as new and desire to secure by Letters Patent is:

1. A refuse bag holder comprising a support; a pair of jaws each having means for holding a bag along opposite portions of the mouth thereof; a pair of arms at each end of the pair of jaws, there being an arm to mount each jaw in operative position; said arms each being separately, pivotally mounted on one face of the support, said arms being substantially L-shaped and each provided with a gear at the free end of the base leg thereof, said gear of each pair being in mesh to insure simultaneous movement of the arms about their pivotal connections when the jaws are shifted toward and from each other to close and open the bag held thereby; and a spring inter-

connecting one of these arms and said support for yieldably holding the arms in either the open or closed position.

2. A refuse bag holder comprising a support; a pair of jaws each having means for holding a bag along opposite portions of the mouth thereof; a pair of arms at each end of the pair of jaws, there being an arm to mount each jaw in operative position; said arms each being separately, pivotally mounted on one face of the support, said arms being substantially L-shaped and each provided with a gear at the free end of the base leg thereof, said gear of each pair being in mesh to insure simultaneous movement of the arms about their pivotal connections when the jaws are shifted toward and from each other to close and open the bag held thereby, one of the arms having a spring for yieldably holding the arm in either

the open or closed position; and a pin on said one face of the support, one of the arms engaging said pin to limit the movement of the arms about their pivotal supports in one direction, the jaws being in side-by-side abutting relation when the arms are at the opposite ends of their paths of travel.
